UNITED STATES PATENT OFFICE.

HERBERT E. MAINE, OF PROVIDENCE, RHODE ISLAND.

SHOE-SIZER.

1,252,920.

Specification of Letters Patent. Patented Jan. 8, 1918.

Application filed September 1, 1917. Serial No. 189,407.

To all whom it may concern:

Be it known that I, HERBERT E. MAINE, a citizen of the United States, residing at Providence, in the county of Providence,

5 State of Rhode Island, have invented certain new and useful Improvements in Shoe-Sizers, of which the following is a specification.

10 My invention is an improved shoe-sizer for measuring the feet and calculating the sizes of shoes required therefor. The object of my improvement is to provide a device of this type which when applied to the foot will indicate at a glance the exact size of 15 shoe required without computing allowances for extra sizes between the length of the foot and the length of the shoe. Another object of the improvement is to provide for a more convenient reading of the shoe size without 20 liability of error or inaccuracy.

The invention is fully described in the following specification, illustrated by the accompanying drawings, in which like reference characters designate like parts. In the 25 drawings:—

Figure 1 is a plan view of my improved shoe-sizer showing one embodiment of the invention;

Fig. 2, a similar view showing a slightly 30 modified arrangement of the sizing-scale and indicator; and

Fig. 3, a longitudinal, side elevation of the device.

Referring to the drawings, B designates 35 a flat bar or measuring-stick on which are two gages or blocks C and D which may be applied to position against the heel and toe of the foot. The heel-block C is preferably fixedly secured at one end of the stick B, 40 while the toe-block D is slidable therealong to adapt it to coöperate with a scale S marked on the top of the stick. As herein shown the blocks C and D are constructed of wood with thin strips F of metal bent 45 around to inclose the stick B and fastened to their sides by the nails or screws f. The sides of the metal strip F on the heel-block C are secured fast to the sides of the stick B by means of screws g, see Fig. 3, to 50 hold the block in fixed position thereon, but the strip F on the movable block D is free to slide along the stick while serving as a guide for the block. At the outer end of the stick B is a button-like stop H comprising 55 a rubber washer h secured in place by a tack h' to limit the movement of the block D to

prevent it from sliding off the end of the stick. A hole k is also provided in the end of the stick B by which it may be suspended on a nail or hook when not in use.

60 Preferably the blocks C and D have relatively broad, flat bases to provide extended bearing surfaces on the upper face of the stick B so that the fixed one C may be secured more rigidly thereto and whereby the 65 movable one D will slide more freely thereon. On their outer sides the blocks C and D are tapered or curved from the base toward the top to reduce their weight, while on their inner sides their faces are straight and 70 perpendicular to the stick B where they sit against the foot. The form and arrangement of the blocks C and D may be varied, however, if desired, the construction herein shown and described not being essential to 75 the present invention.

My present improvement consists particularly in the method of coöperation between the sliding block D and the scale S whereby the exact size of the shoe is indicated at 80 the forward edge of the block when its opposite, rearward side is adjusted against the longest toe of the foot as the sole is pressed against the top of the stick with the heel against the fixed block C. The scale S is 85 graduated in accordance with standard sizes of shoes generally used in the trade with three sizes to the inch, the full sizes being indicated by long marks s and the half-sizes by intermediate, shorter graduations s'. The 90 graduations are marked from the rear to the front along the scale S by figures running in sequence from 1 to 13 for boys' and girls' shoes, and at the forward end from 1 to 14 for men's and women's sizes. 95

Referring particularly to Fig. 1, when the heel of the foot is placed against the straight side of the fixed block or stop C and the sliding block D is adjusted against the end of the longest toe, the inner face of the 100 block D will register with one of the graduations on the scale S to indicate the exact length of the foot as expressed in shoe sizes. With all previous shoe-sizers it is necessary to take this reading from the inside of the 105 block D and to add to it a certain number of extra sizes to arrive at the size of shoe required. For instance, supposing the foot to measure $3\frac{1}{2}$ sizes on the men's and women's scale as indicated by the position of the 110 block D in Fig. 1. Now, if the foot is being measured as extended, that is with the per-

son standing with his weight on it, two sizes are added to give the required shoe-size; or, in case the foot is being measured without the person's weight on it, then two and one-half sizes are added. As shown in Fig. 1, therefore, since the block D registers with the graduation corresponding to size $3\frac{1}{2}$, then the size of shoe required is $3\frac{1}{2}$ plus 2, or plus $2\frac{1}{2}$, as the case may be. That is to say, if the foot is measured off the ground, as is the usual custom, then the fitter will add $2\frac{1}{2}$ sizes to the size indicated at the inner side of the block D, giving $3\frac{1}{2}$ (as measured) plus $2\frac{1}{2}$ (allowance) or size 6 for the shoe required. With my improved shoe-sizer this allowance or addition to the reading of the scale is not required. It is to be noted from Fig. 1 that the width of the block D is equal to two and one-half full spaces or graduations on the scale S and consequently when the rearward edge of the block D registers with any certain graduation the front face of the block will register with a mark $2\frac{1}{2}$ sizes larger. Therefore, instead of reading the scale at the back or rearward edge of the block D the operator reads from the front edge and thus arrives at the exact size of shoe required without computing allowances. It is obvious that it will be much easier to read the scale S at the front of the block D than at its rearward edge, and this can be done while the device is still applied to the foot so that there is less chance for error or inaccuracy. On the other hand, with all previous forms of shoe-sizers the gage-block must be held carefully in place while it is removed from the foot before the scale can be read. This is not only inconvenient, but tends to cause error and inaccuracies in the reading, and besides the operator must always make a calculation for allowances, as above explained, so that there is added opportunity for mistakes. With the present, improved apparatus the operator has simply to apply the fixed block C to the heel of the foot being measured, with the scale S under the sole, and by sliding the movable block D back against the toe the proper shoe-size will be indicated at the front of the block where it can be read at a glance without chance of error and without requiring calculation.

In Fig. 2, I have illustrated a slightly modified arrangement of the block D and scale S whereby the structure of the device is improved to some extent as next explained: It is desirable that the block D be made of considerable width on its base in order that it will slide easily along the stick B without cramping or binding thereagainst. For this reason it is preferable to make the block wider than two and one-half spaces on the scale S and therefore I have adopted for general use a width equal to three and one-half spaces as shown in Fig.

2. With this width of block I set the scale S one space farther down on the stick B, or, in other words, the numbers on the graduations are advanced one full space on the scale in relation to the fixed block D. With this arrangement, when the block D is adjusted to measure any certain size of foot, its inner edge will indicate one number under the correct size, but its outer edge will still give the exact size of shoe required. For instance, as shown in Fig. 2, the inner edge of the block indicates $2\frac{1}{2}$ sizes instead of $3\frac{1}{2}$, but the outer edge is still on the mark 6 because the size of foot measured is the same as that for which the device shown in Fig. 1 is set, namely $3\frac{1}{2}$, requiring a size 6 shoe. It will be understood, of course, that the size of the foot itself is not needed, but only the size of the shoe required to fit the foot. That is to say, the shoe-sizes are not the same as the foot-sizes, but ordinarily must be arrived at through calculation. In my present improvement the device itself performs the computation, indicating the exact shoe-size at a glance without any calculation on the part of the operator. For this reason it is much more accurate and reliable than similar devices previously used for the same purpose. Usually the device carries a legend at L giving directions for using it and these are so simple that an inexperienced person may operate it without the slightest chance of misunderstanding or mistake. As before stated, the size of shoe required is indicated instantly without computation or calculation, and therefore the apparatus is much more convenient and easy to use.

Various modifications might be made in the form and structure of the parts of my device without departing from the spirit or scope of the invention. Therefore, without limiting myself to the exact embodiment shown, what I claim is:—

1. In a device for measuring feet and computing the required sizes of shoes therefor, the combination with a measuring-stick, of a heel-block fixed at one end thereof, a toe-block slideable along the stick toward and away from the fixed block, and a scale with which the sliding block co-operates, said scale being graduated in accordance with standard shoe-sizes and the block adapted to register with the graduations at both its rearward and forward sides whereby to add the allowance between the length of the foot and the length of the shoe to indicate the proper size of the latter at the front of the block in convenient position for instant reading.

2. In a shoe-sizer, the combination with a measuring-stick having a scale on its face, of a heel-block fixed in position at one end of the stick, and a toe-block adjustable along the stick toward and away from the fixed

block, the scale on the stick being graduated in accordance with standard shoe-sizes and the sliding block being of a width to adapt its forward edge to register with a certain

5 graduation when its rearward edge registers with the graduation corresponding to the length of the foot, whereby the extra size al-

lowance is added simultaneously with the measuring to indicate the exact size of shoe required without calculation on the part of 10 the operator.

In testimony whereof I affix my signature.

HERBERT E. MAINE.
